UNITED STATES PATENT OFFICE.

FREDERICK WILLIAM WARDEN PICKANCE, OF WIMBLEDON, LONDON, ENGLAND.

VENTILATING APPARATUS.

Application filed March 26, 1924, Serial No. 702,070, and in Great Britain May 17, 1923.

The object of this invention is to provide means whereby the amount of air which is induced to flow into a room or circulate therein, and more particularly its humidity, 5 can be varied.

In carrying out my invention I provide a casing in which is located an atomizer which forms a divergent stream or jet of compressed humidified gas, such as air, which is 10 directed towards an outlet from the casing, and means are provided for moving the outlet and the atomizer relatively to one another whereby the quantity of air induced to flow through the casing and consequently 15 its humidity is accurately controlled.

In one form of construction the outlet from the casing is formed of a cone, the position of which can be altered by a rack and pinion graduated to indicate the amount 20 of air induced by the atomizer under given conditions.

The atomizer may be so constructed that the water or other liquid is sprayed or atomized by a ring of compressed air or other 25 gas, means such as a needle valve being provided for regulating the quantity of liquid.

With apparatus constructed in this manner, if the relative position of the atomizer and the casing outlet be varied without 30 altering the position of the needle valve, then the humidity of the air will be varied as well as the quantity of air induced; the humidity of the air can, on the other hand, be varied by varying the position of the 35 needle valve without altering the relative position of the atomizer and casing outlet. The ventilation of a room and the humidity of the air therein can consequently be maintained or altered to suit any desired condition, irrespective of the condition of the air 40 outside the building.

In practice, the desired condition of the air in a room can usually be most readily effected by keeping the pressure of air supplied to the atomizer and also the quantity 45 of water atomized constant, and by altering the position of the cone to regulate the humidity of the induced air.

Obviously air from a refrigerating plant 50 can be admitted to the casing.

In the accompanying drawing which illustrates the invention, Figure 1 is a side elevation, Figure 2 a plan of Figure 1, Figure 3 an end elevation, Figure 4 a detail section 55 to a larger scale, and Figures 5 and 6 views of a modification.

1 is a casing at the forward end of which is located an atomizer 2 which can be supplied with water or other liquid through a pipe 3 and with air or other gas under pressure through a pipe 4.

The water is conducted to a hollow cone 5, the quantity of water induced by the air being regulated by a needle valve 6 having an actuating knob 7.

The air is led through passages 8 to an annular conical space formed between the outer surface of the cone 5 and a nozzle 9, and issues from the nozzle in the form of a divergent cone which can be humidified to 70 any desired extent by adjusting the needle valve 6.

10 represents the outer wall of a building having an aperture through which the rear 75 end of the casing 1 projects.

The rear end of the casing 1 is open but can be controlled by means of a cone 11 mounted on slides 12 which can be adjustably fixed in position on the casing by means of wing nuts 13.

The casing 1 is also provided with an inlet 14 opening into the room or building in which the apparatus is fixed.

In order to control the quantity of air admitted from outside the building or from 80 the room, the casing is provided with shutters 15, 16, pivoted to the casing at 17, 18, respectively. The shutter 15 can be actuated by a lever 19, one end of which is adapted to engage stops on the quadrant 20, 90 while the other end is connected by a link 21 to an arm 22 connected to the shutter 16 in such a manner that as the shutter 15 is opened so the shutter 16 is closed, and vice versa.

23 is a cone having an extension 24 slidably mounted in the casing 1. Fast on the cone 23 are racks 25 meshing with which are pinions 26 mounted on shafts 27, the ends of which latter are provided with bevel wheels 28 in mesh with bevel wheels 29 on a shaft 30 having an actuating wheel 31.

The casing is also provided with guides 32 which guide the cone. The said guides are calibrated to indicate the amount of air 105 which will be induced to flow through the cone 23 for a given pressure of compressed air supplied to the atomizer, and/or calibrated to indicate the humidity for a given pressure of compressed air and a given position of the needle valve 6.

In the modification shown in Figures 5

and 6, the casing 1 is provided (in place of the inlet 14) with openings 33 which can be uncovered or closed by a sleeve 34 which latter is provided with a pin 35 engaging a slotted lever 36 fast on the pivot 17 and so shaped that the openings 33 are closed as the shutter 15 is opened.

37 shows diagrammatically a heater by means of which the incoming air can be heated. 38 shows diagrammatically filters of any suitable construction which may be fitted when desired.

In operation the amount of air which is caused to flow through the cone 23 is regulated by moving the said cone to or from the nozzle 9 of the atomizer. When the cone 23 is in the position shown, the smallest amount of air of which the apparatus is capable of delivering is delivered (when air at a given pressure is employed). As the cone 23 is moved away from the nozzle 9, an increasing amount of air is induced to flow.

Preferably the cone 23 is so proportioned that when it is in its extreme forward position the diameter of the outer end thereof is slightly greater than the diameter of the divergent stream of compressed air (whether humidified or not) issuing from the nozzle 9 at this point.

Since the amount of liquid supplied to the atomizer is constant, if the needle valve 6 be unaltered, the humidity of the air flowing through the cone 23 varies as the position of the cone is altered. If it be desired to keep the quantity of air flowing through the cone 23 constant, but to vary the humidity thereof, this is effected by adjusting the needle valve 6 by means of the actuating knob 7.

It should be noted that for any given position of the cone 23, the amount of air induced to flow is only very slightly altered, if at all, when the amount of liquid flowing through the nozzle 9 is altered, provided that the pressure of the air supplied to the pipe 4 is constant.

What I claim is:—

1. Apparatus for ventilating a building comprising a casing, means within said casing for creating a divergent stream of air under pressure, means for admitting liquid to said stream whereby the liquid is atomized and mixed with the air, means for admitting air to said casing, an outlet for the casing, and means for obtaining relative movement between the outlet and the means for creating the stream so as to vary the amount of the mixture induced by the said stream to flow through the outlet.

2. Apparatus for ventilating a building comprising a casing, means within said casing for creating a divergent stream of air under pressure, means for admitting liquid to said stream whereby the liquid is atomized and mixed with the air, means for ad-

mitting air to said casing, an inwardly flared cone forming an outlet for the casing, means for obtaining relative movement between the outlet and the means for creating the stream so as to vary the amount of the mixture induced by the said stream to flow through the outlet.

3. Apparatus for ventilating a building comprising a casing, means within said casing for discharging a humidified stream of air under pressure, an inlet to the casing from outside the building, an inlet to the casing from inside the building, an outlet from the casing into the building, means for varying the area of either of said inlets, and means for obtaining relative movement between the outlet and the means for discharging said stream so as to vary the amount of air induced by said stream to flow through the outlet.

4. Apparatus for ventilating a building comprising a casing, means within the casing for discharging a humidified stream of air under pressure, an inlet to the casing from inside the building, an inlet to the casing from outside the building, means for varying the area of said inlets so that the area of one inlet varies inversely as that of the other, an outlet from the casing, and means for varying the position of said outlet relative to the air discharging means.

5. Apparatus for ventilating a building comprising a casing, means within the casing for discharging therefrom into the building a humidified stream of air, means for controlling the degree of humidity of the air by varying the amount of liquid admitted thereto, and means for controlling the humidity by varying the amount of air caused to flow through the casing.

6. Apparatus for ventilating a building comprising a casing, means within the casing for discharging a humidified stream of air under pressure, an inlet to the casing from within the building, an outlet from the casing to the building, and means for varying the relative position of the outlet and said first named means.

7. Apparatus for ventilating a building comprising a casing, means within the casing for discharging a humidified stream of air under pressure, an outlet to the building from the casing, means for controlling the humidity of the air by varying the amount of moisture admitted to said humidified stream, and other means for controlling the humidity of the air by varying the relative position of the outlet and the first-named means thereby varying the amount of induced air.

In testimony that I claim the foregoing as my invention I have signed my name this fifth day of March 1924.

FREDERICK WILLIAM WARDEN PICKANCE.
